CLAIM

The ornamental design for a hockey puck display case as shown and described.

DESCRIPTION

FIG. 1 is a perspective of a hockey puck display case showing our new design;

FIG. 2 is a front view of the display case;

FIG. 3 is a right side view of the display case;

FIG. 4 is a top plan view of the display case;

FIG. 5 is a rear view of the display case;

FIG. 6 is a left side view of the display case; and,

FIG. 7 is a bottom plan view of the display case.

The elements shown in phantom form no part of the claimed design.
